AUTOMATIC PORTABLE DERRICK

George Haniquet, Glendale, Calif.

Application December 29, 1938, Serial No. 248,353

13 Claims. (Cl. 254—139)

This invention relates to improvements in derricks, particularly of the type which can be readily transported from place to place. The particular adaptation in mind of the invention is to telephone work. It is common practice for a telephone erecting crew to raise a telephone pole in the hole by the use of a fairly large number of handled spikes.

These spikes are of various lengths, and each requires a man for its manipulation. The erecting crew can thus easily comprise a dozen or more men and the raising of the pole is not done with any particular speed or facility.

This particular type of work can be done quite expeditiously by supplementing the truck with a derrick which is sufficiently light not to impose much of an extra burden on the equipment. A derrick so employed naturally reduced the number of men required for an individual operation so that some of the men ordinarily demanded to complete a crew can be diverted to other and equally important work.

The matter of lightness of the derrick has been touched upon. Although this is a prerequisite it is equally important to be sure that the boom is of adequate strength to handle any ordinary size of pole. In this respect the use of the invention is not limited to telephone work because the derrick can be pressed into service wherever light hoisting is to be done. The structure is such that no energy on the part of the crew has to be spent in raising the derrick to its working position. When the boom is released it rises immediately to its working position in a manner which is brought out below. With this premise in mind the objects of the invention are as follows:

First, to provide a portable derrick which is subject to automatic raising into an erect position in respect to its carrier when released from the clamp which normally holds the boom down.

Second, to provide a derrick of the type adapted to be mounted upon and carried by a truck, one of the features of the derrick consisting of a spring motor for automatically raising the boom from a horizontal non-working position upon the truck to an erect and working position in respect to the truck and ground.

Third, to provide a derrick in which a load-limiting device is embodied in the boom, said device being coupled with an appropriate means for automatically opening an auxiliary ignition switch if the boom is put under a load so great that the raising of it will endanger the mechanical structure.

Other objects and advantages will appear in the following specification, reference being had to the accompanying drawings, in which:

5 Figure 1 is a side elevation of the improved automatic portable derrick, illustrating how it may be mounted upon an automotive truck.

Figure 2 is a cross section taken on the line 2—2 of Fig. 1.

10 Figure 3 is a fragmental side elevation illustrating the automatic raising act when the boom is released.

Figure 4 is a side elevation, parts being shown in section showing the boom in its erected position.

15 Figure 5 is a longitudinal section of the spring motor taken substantially on the line 5—5 of Fig. 1.

Figure 6 is a horizontal section taken on the line 6—6 of Fig. 5.

20 Figure 7 is a partially sectional and elevational view of the free end of the boom, particularly illustrating the load-limiting device, and also illustrating the rope guard.

Figure 8 is a section taken on the line 8—8 of Fig. 7, but showing the parts as though the derrick boom were in the erect position.

25 Figure 9 is a cross section taken on the line 9—9 of Fig. 7, particularly illustrating the rope keeper.

30 Figure 10 is a cross section taken on the line 10—10 of Fig. 7.

Figure 11 is a cross section taken on the line 11—11 of Fig. 1 illustrating one of the boom rests.

35 Figure 12 is a cross section taken on the line 12—12 of Fig. 1 illustrating the boom clamp as well as another boom rest.

Figure 13 is a detail sectional view of the foot end of the boom.

40 In carrying out the invention provision is made of a boom generally designated 1. This boom comprises an outer tube 2 of a suitable metal, either round or non-circular in cross section. This tube is open at its free and foot ends 3, 4. These terms are adopted mainly for the purpose of distinction, the foot end 4 actually being as free as is the so-called free end 3.

45 A telescopic tube 5 is slidably fitted in the foot end 4. Attention is directed to Fig. 13 for the structural details at this end. The telescopic tube 5 has a heavy internal thread 6 into which a screw 7 is driven. This screw has a head 8 which terminates in a ball 9. The ball is swivelled in a socket 11 on a foot plate 10. This plate is adapted to rest on the ground (Fig. 4).

the ball and socket connection 8, 9 enabling its adaptation to any uneven surface.

A short double-headed rod 12 is slidably fitted in a hole 13 in the head 8 of the screw 7. This rod is for the purpose of facilitating the turning of the screw 7 so as to either extend it from the telescopic tube 5 or to drive it in. This provision also compensates for differences in elevation of the ground surface.

Further extension of the foot plate 10 with respect to the boom tube 2 is provided by selectively fitting a key 14 (Fig. 13) into any one of a set of holes 15 in the tube 5. The latter is slotted at 16 and a pin 17 affixed at its ends in the tube 2, occupies the slot 16 to limit the extension of the tube 5.

At the free end 3 of the boom tube 2 there is a load-limiting device commonly designated 18 (Fig. 7). This device consists of a tubular insert 19 which has an integral partition 20 contiguous to its inner end and carries a sheave fork 21 at its outer end. The sheave fork consists of duplicate plates 22 (Fig. 8) which are made integral with a plate 23. This plate is welded to the tubular insert 19 so as virtually to be an integral part of said insert. Matching slots 24 in the insert 19 make room for a cross bolt 25 which limits the extension of the insert 19 under the influence of a heavy spring 26 which presses against the partition 20.

For the purpose of the spring the boom tube 2 also has a partition 27 against which the spring 26 is rested. An electrical switch 28 is attached to the partition 27. This switch may comprise an ordinary closed type automobile stop light switch. It has a movable plunger 29. One end of this plunger projects through a hole 30 in the partition 27 because of the tension of a spring (not shown) which tends to keep the plunger in the projected position. A stud 31 on the partition 20 is adapted to be held spaced from the plunger 29 by the spring 26. When an overload is imposed on the sheave in the fork 21, the recession of the tubular insert 19 into the boom tube 2 against the tension of the spring 26 brings the stud 31 into engagement with the plunger 29, a sufficiently continued movement actuating the switch 28 to open an electrical circuit, herein regarded as comprising the ignition circuit of the truck engine E (Fig. 7). This circuit is commonly designated 32.

The wires of this circuit embrace an ignition switch 33 and a relay 34 which acts in the capacity of an auxiliary ignition switch. When the ignition switch 33 is manually closed the resulting magnetization of the relay core attracts the relay armature 35 and completes the ignition circuit which can be traced through the spark coil and timer (both designated, Fig. 7). The relay may be conveniently mounted anywhere on the carrier of the boom, for example on the dash-board (not shown) of a truck 36. The engine E is adapted to operate a hoisting means, which may consist of the drum 36a on the engine shaft. One end of a hoist cable 36b is wound on this drum, said cable being trained over the sheave 38, mounted in the fork 21.

As long as the derrick is being operated under safe conditions the switch 28 remains closed, but when the derrick is subjected to an overload in the manner indicated, the depression of the plunger 29 and consequent opening of the switch 28 will automatically open the ignition circuit 32 and stop the engine E. Said opening of the

switch 28 and circuit 32 deenergizes the relay 34 to accomplish the purpose stated.

The plates 22 of the fork 21 (Fig. 8) provide the supports for the axle 31 of the sheave 38. The axle has reduced ends 39 one of which goes through a hole 40 in one of the plates 22. The other plate has a larger hole 40a receiving the axle itself. A collar 44 on that end of the axle adjacent to the hole 40a provides a stop to set the position of the axle. No matter how tightly the nuts 41 are screwed onto the threads 42 of the ends 39, there will not be any binding of the plates against the sheave, provided that the large part of the axle 31 is made slightly longer than the hub of the sheave.

Eyes 43 for guy ropes (not shown) are slipped onto the ends 39 against the collar 44, and a washer 44a. The collar and washer space the eyes far enough away from the plates 22 to make a room for the outer ends of a pair of braces 45. The respective lower and upper ends of these braces are respectively welded to the rim of the plate 23 and to the plates 22 contiguously to the collar 44 and washer 44a, thus fortifying the plates 22 against bending under any ordinary circumstance. The fork 21 has branches 46, 47 (Fig. 7), the first pair of which is adapted to be bridged by a rope keeper 48 (Fig. 9). One end of this keeper and one of the branches 46 is hingedly connected at 49 so that the keeper can be swung across or away from the sheave 38.

The other end of the keeper has a lip 50 (Fig. 9) which is adapted to be engaged by a spring latch 51. This latch is riveted to the companion branch 46. The extremities of the pair of branches 47 are bridged by a quickly removable pin 52 which is held in place by a cotter pin 53. The rope or cable 36b (Fig. 7) is easily applied to the groove in the sheave 38 by removing the pin 52. The keeper 48 is preferably made movable so as to facilitate applying the cable to the sheave. The particular purpose of the keeper is to prevent the rope from jumping the sheave, it being noted that the keeper 48 is located on that side of the boom 1 which eventually becomes the outside. This circumstance can readily be understood by comparing Figs. 1 and 4.

The assemblage described up to this point is mounted on a frame 54 (Figs. 1 and 2). The boom tube 2 in particular is secured to this frame. The telescopic tube 5 and the tubular insert 19 obviously cannot be secured to the frame because of the necessity of their independent motion relatively to the boom tube. The latter has at least one bolt 55 secured through it, and through the collars 56, 57 of pairs of diverging bars 58, 59. The erect bars 58 are shown only in part in Fig. 2. These bars are riveted to extensioners 60 of the collars 56, 57 and in order to make the connection of the collars to the tube 2 as secure as possible bolts 61 are applied to draw the pairs of bars and the extensions of the collars tightly together.

The frame 54 is connected to an elevating mechanism generally designated 62. This mechanism comprises a spring motor (Figs 5 and 6). It is adapted to automatically erect the boom 2 (Figs. 3 and 4) when the latter is released. The spring motor also functions to resiliently support the boom in its erect position. Attention is directed to Figs. 5 and 6 for the details of the elevating mechanism.

A base plate 63 is secured at 64 (Fig. 1) to the floor 65 of the truck 36. This plate has a pair of standards 66, 67 (Fig. 5) of which the stand-

ard 67 is highest so as to conform to the obtuse angle at which these standards stand in respect to the plate 63. Said standards have matching holes 68 which provide bearings for a shaft 69. The shaft 69 is perpendicular to the standards and as a consequence of the setting of the standards in respect to the base plate 63 the shaft 69 is supported at a pitch. This pitch disposes the boom 1 at an incline both to the rear of the truck 36 (Fig. 4) and to the side of the truck when the boom is erected, the position thus assumed by the boom being most advantageous in raising a telephone pole.

In order to make this standing of the boom a little more clear, it is readily seen in Fig. 4 that the elevating mechanism 62 can be so located in respect to the tail of the truck as to stand the boom on a rearward incline when it has been raised. The standard 66 comes nearest the right side of the truck, the standard 67 being farther toward the center. The shaft 69 is thus pitched toward the right side of the truck, this accounting for the outward pitch of the erected boom with respect to the truck side.

Reverting to Fig. 5, the shaft 69 carries hollow bolts 70 near its threaded ends 71. The heads 72 of these bolts provide spacers between the standards 66 and the bar members of the frame 54. The said bar members are emplaced upon the bolts 70, the former having common holes 73 to receive the bolts, whereupon nuts 74 are screwed down tight on the threaded ends of the bolts against the bar members so as to virtually convert the bolts 70 into hubs for the frame 54.

The assemblage at these points is completed by screwing nuts 75 onto the threaded ends 71 of the shaft 69. These nuts are lightly fitted against the tips of the hollow bolts 70 so as not to interfere with the turning of the so-called hubs 70 and spring housings as a unit upon the shaft 69.

A pair of spring housings 76, 77 is carried by the frame 54. Each of these housings consists of a cylindrical casting having a flange 78 on one end and an internally threaded rabbet 79 on the other end. A disk 80 is screwed into the respective rabbet to constitute a closure for one end of the spring housing. The flanges 78 are bolted at 81 to the bars 58, 59 of the frame 54, sleeves 82 being slipped on the bolts between the flanges 78 and the respective arms to constitute spacers (Fig. 5). The frame 54, hollow bolts or hubs 70 and spring housings 76, 77, thus comprise a turnable unit as indicated above.

The mode of assembling the foregoing parts of the unit is well illustrated in Fig. 5. The flanges 78 are necessarily remote from each other, the closure disks 80 being in confronting relationship. These disks have elongated holes 83, 84. Similar holes 85, 86 occur in the standards 66, 67, contiguously to the open ends of the spring housing.

The latter contain heavy coil springs 87, 88. These springs are similarly wound. They are disposed in tandem as illustrated in Figs. 5 and 6, and the convolutions thereof are pitched in a common direction. The respective springs 87, 88 have hook terminals 89, 90 and 91, 92. These terminals are connected to the standards which provide a common anchorage, and to the spring housings in the serial order of the holes 86, 83, 84 and 85.

The springs 87, 88 naturally have an inherent tension. They are so coupled to the boom movable frame 54 and the stationary standards 66, 75

5 67, that the spring 88 is virtually dormant when the boom 2 is in its inactive position (Fig. 1) and that the spring 87 is under a supertension in the same position of the boom. In other words, the spring 87 is wound at this time while the spring 88 is virtually unwound.

This supertension in the spring 87 constitutes a source of latent energy which will raise the boom when the latter is released. To this end the truck 36 carries a pair of rests 93, 94 (Figs. 11 and 12) which, together with a strut 95 branching off from the rest 94 (Fig. 1), carry a gutter 96 in which the boom is adapted to fit. One of the rests, for example the rest 94, is provided with a clamp 97 hinged at 98 and adapted to be swung down over a hasp 99 through which either a pin or the shank of a lock can be inserted.

When the boom 2 is unclamped at 97, it immediately starts to rise because of the supertension of the spring 87. When the boom has reached the erect position (Fig. 4) it is secured there by means of a hook 100. This hook is swung on its pivot 101 to engage the eye 102 of a plate 103 on the back of the truck. The hook has a long handle 104 and after engagement is made with the eye 102 the handle is slipped under a spring catch 105. Both the spring catch and the hook are attached to the frame 54.

30 The operation is readily understood. It was previously stated that the spring 87 is wound and the spring 88 is unwound when the boom 2 is in the lowered and inactive position in Fig. 1. Thus the spring 87 constitutes a positive power member and the spring 88 a negative power or shock absorber member. Upon releasing the boom by disconnecting the clamp 97 there is an immediate automatic upward swing due to the stored tension in the spring 87. The unwinding of the spring 87 will raise the boom toward its erect position. When the boom reaches a position approximately medially of its prone and erect positions, the winding of the spring 88 commences. The momentum of the boom in its upswing is thus absorbed by the winding of the spring 88.

The hook terminal 89 of the spring 87 is anchored to the standard 67 (Fig. 6) and does not partake of any motion. The terminal 90 moves in the direction of arrow *a* when the boom is released, as stated. The unwinding of the spring 87 causes turning of the frame and housing assemblage in the counterclockwise direction (arrow *b*, Fig. 3).

55 Since the terminal 91 of the spring 88 is propelled in the direction of arrow *c* (Fig. 6) it follows that winding of the spring 88 will commence as stated, the terminal 92 of the latter being anchored to the standard 66. When the boom reaches the half way position (Fig. 3) while still swinging in the direction of arrow *d*, the springs 87, 88, will be at an approximate equilibrium. The spring 87 will be substantially unwound and the spring 88 is about to be wound. But the boom 2 and its frame 54 are fairly heavy and the momentum imparted thereto by the initial unwinding of the spring 87 is sufficient to carry the boom to the erect position (Fig. 4) and at the same time to completely wind the spring 88.

60 As the spring 88 becomes wound more tightly it will take the weight of the boom when in the vertical position. It acts as a shock absorber, preventing the foot plate 10 from driving hard against the ground and thus jarring the derrick unnecessarily. By the time the boom reaches

the erect position, the spring 28 will have the same supertension that the spring 27 had initially, the spring 27 then being practically unwound. The stored tension in the spring 28 is ultimately used to automatically lower the boom and this is accomplished by releasing the hook 188 from the eye 182.

The cable 36b (Fig. 7) is applied to the sheave 38, the free end of the cable being attached to the load. The engine E may be either the engine for propelling the machinery of the truck, or it may comprise an independently carried power device. In either event it is adapted to operate a hoisting means, shown to comprise the drum 36a. The engine is controlled by the ignition circuit 32 which, as previously explained, is maintained in the closed position by the normal closure of the switch 28. The spring 26 resists the recession of the insert 19 inwardly of the boom 1, but when the load imposed on the sheave 38 exceeds the tension of the spring 26, the collapse of the latter results in an opening of the switch 28, an opening of the ignition circuit 32, and the stopping of the engine E. The automatic control thus afforded is regarded as being of considerable importance in that it insures the avoidance of damage to the derrick mechanism.

In conclusion it is desired to point out that the erecting principle of the invention is not necessarily confined to a portable derrick. The boom 1 may constitute any equivalent carrier, for example, a ladder. It is readily conceivable that if the boom were substituted by a ladder, the device would be well adaptable as an auxiliary to fire fighting apparatus. The ladder, if the carrier were so constructed, could be easily, quickly, and effectively erected, the mode of operation then followed being identical with the description of the latter already set out.

I claim:

1. A derrick comprising a boom, a frame to which the boom is rigidly secured, and elevating mechanism for erecting the boom, including positive and negative power members, means commonly connecting a portion of said power members to the frame thus to build up the negative power member simultaneously with erecting the boom by spending the positive power member, and an anchorage to which other portions of said members are also commonly connected.

2. A derrick comprising a boom, a frame to which the boom is rigidly secured, elevating mechanism for the boom including a spring under initial tension to constitute a power member, clamps means for holding the boom down against the tension of said spring, said clamp means being disconnectible to release the boom for automatic movement to an erect position, and a spring initially relaxed to constitute a shock absorbing member, being put under tension by said boom to check its movement as the boom nears its erect position.

3. A derrick comprising a boom, a frame to which the boom is rigidly secured, elevating mechanism for the boom consisting of a pair of similarly convoluted springs, one of the springs being wound, the other spring being unwound and both of the springs having terminals, said springs being disposed in tandem so that their convolutions are pitched in a common direction, means by which the spring terminals nearest each other are coupled to the frame, and rigid means turnably supporting the frame and pro-

viding an anchorage for the other and remote terminal of the springs.

4. A derrick comprising a boom, a frame to which the boom is rigidly secured, supporting means on which the frame is turnable, and elevating mechanism for the boom comprising a spring couple, one of the springs being under supertension the other spring being under neutral tension, each of the springs having a pair of terminals connected to the respective frame and supporting means.

5. A derrick comprising a boom, a frame and shaft assemblage to which the boom is rigidly secured, supporting means turnably carrying the shaft of said assemblage at a pitch to a floor to which said means is adapted to be secured, thereby to stand the boom at an inclination to said floor when erected, and elevating mechanism for said boom including a spring with two terminals, one of the terminals being connected to the supporting means, the other terminal being connected to the frame and shaft assemblage.

6. A derrick comprising a boom, a base plate having a pair of standards upstanding from the base plate at an obtuse angle, a shaft supported by said standards in perpendicularity thereto thereby disposing the shaft at a pitch to the base plate, and a frame to which the boom is attached, being mounted on said shaft.

7. A derrick comprising supporting means adapted to be stationarily secured to a floor, a frame and shaft assemblage, the shaft portion of which is turnably journaled on said supporting means, a boom rigidly attached to the frame portion of the assemblage, rest means supported by said floor, against which the boom is adapted to be laid in its inactive position, a spring motor coupled to the supporting means and to said assemblage, being under initial tension to raise the boom away from said rest means, and clamp means embodied in the rest means, being adapted to secure the boom to the rest means against the tension of said spring motor.

8. In a derrick, a carrier, a frame to which the carrier is rigidly secured, stationary supporting means to which the frame is hinged, at least one spring housing embodied in the frame and being turnable with the frame on said hinge, and a coil spring encased by the housing, said spring having terminals, one of which is anchored to the supporting means the other terminal being attached to said housing.

9. In a derrick, a boom, a frame to which the boom is rigidly secured, stationary supporting means to which the frame is hinged, a pair of spring housings embodied in the frame and being turnable with the frame on said hinge, and a coil spring within each housing, one being initially supertensioned and the other initially unwound, each of the springs being anchored both to the supporting means and to the respective housings so that the unwinding of the supertensioned spring will tend to put the unwound spring under tension.

10. In a derrick, a boom, a frame to which the boom is rigidly secured, said frame consisting of bars, a pair of spring housings and a shaft constituting a unit to which the bars are commonly secured, a stationary support on which the shaft is journaled thus making the frame turnable to erect the boom, and a spring encased by each one of the housings, each spring having ends respectively anchored to the stationary support and to the respective housing.

11. In a derrick, a boom, a frame to which the

boom is rigidly secured, said frame consisting of plural bars, a stationary support having a shaft journalled therein, hub means connected to the bars and mounted on the shaft, a pair of spring housings concentric to the shaft, having flanges and means by which the flanges are rigidly secured to the frame bars so as to comprise a frame and housing assemblage, and a spring encased by each housing, each spring having hook ends one of which is anchored to the support, the other being anchored to the respective housing.

12. In a derrick, a sheave fork consisting of side plates, each having at least one branch, a

sheave journaled in the fork and having the branches terminating substantially at the perimeter thereof, and a rope keeper bridging the rope passage of the sheave, being hinged at one end to one of the branches.

13. In a derrick, a boom, an axle, a fork carried by the boom supporting the axle, a sheave journaled on the axle, inherently separate eyes to receive guy ropes to stabilize the sheave when the boom is erected, and means commonly securing the eyes to the axle and the axle to the fork.

GEORGE HANIQUET.
